UNITED STATES PATENT OFFICE.

WILBER THOMAS, OF QUINCY, ILLINOIS.

DESIGN FOR A FENCE-PICKET.

SPECIFICATION forming part of Design No. 12,971, dated June 13, 1882.

Application filed April 21, 1882. Term of patent 14 years.

To all whom it may concern:

Be it known that I, WILBER THOMAS, of Quincy, in the county of Adams and State of Illinois, have invented and produced a new and original Design for Fence Pickets, Palings, and the like; and I do hereby declare that the following is a full, clear, and exact description of the invention, which will enable others skilled in the art to which it appertains to make and use the same, reference being had to the accompanying drawings, which form a part of this specification.

This invention has relation to designs for the pickets and palings of fences; and its object is to secure simplicity, novelty, and attractiveness.

To these ends it consists in certain improvements in the contour of the same, substantially as will be hereinafter more fully specified.

In the drawings, Figure 1 is a perspective view of a picket embodying my improved design. Fig. 2 is a sectional view thereof, and Fig. 3 is a fence formed of my ornamental pickets.

Corresponding parts in the figures are denoted by the same letters of reference.

Referring by letter to the drawings, A denotes the picket, the sides of which, B B, are formed convex or bulging across their entire width to the flat square edges C C. The top 30 D of the picket is curved in the form of an arc, the ends of which meet the tops of the flat edges C C, and there form an abrupt or sharp corner, E.

This above-described ornamental picket is 35 designed to be secured in an upright or other position along the longitudinal wires of a fence, as in Fig. 3, and when in position form a simple, attractive, and neat fence at little expense.

I claim and desire secure by Letters Patent—

The improved design for ornamental fence pickets, palings, and the like, herein shown and specified.

In testimony that I claim the foregoing as 45 my own I have hereto affixed my signature in presence of two witnesses.

WILBER THOMAS.
